UNITED STATES PATENT OFFICE

CHARLES G. PASSANANTE, OF JERSEY CITY, NEW JERSEY

FOLDING TABLE

Application filed August 13, 1931. Serial No. 556,896.

This invention relates to certain new and useful improvements in folding tables, and the primary object of the invention is to provide means whereby the hinged legs of the table may be readily, easily, conveniently and compactly folded relative to the top of the table.

A still further object of the invention is to provide a legged supporting structure for tables, chairs, pedestals and the like wherein the legs are hingedly connected to the work supported, and are so connected with one another as to facilitate the swinging of the legs from a supporting to a non-supporting or folded position and vice versa; and further whereby the legs may be swung to either of the above named positions simultaneously one with the other.

Other objects and advantages of the invention will become apparent from a study of the following description, taken in connection with the accompanying drawings, wherein:

Figure 1 is a bottom plan view of a table embodying the features of the present invention, the legs being shown folded inwardly to a non-supporting position.

Figure 2 is a vertical transverse fragmentary sectional elevational view through the table illustrating certain features of the invention to be hereinafter more fully referred to.

Figure 3 is an elevational view of the table.

Figure 4 is a fragmentary sectional elevational view showing the manner of hingedly mounting the leg and hinge connector.

Figure 5 is a fragmentary detail sectional elevational view taken substantially on the line 5-5 of Figure 1.

Figure 6 is a sectional elevational view taken substantially on the line 6-6 of Figure 3.

With reference more in detail to the drawings, it will be seen that in the illustrated embodiment of the invention, the table comprises the top member 10 mounted within a rectangular frame 11. Although I have here referred to the member 10 as being the top of a table, it is to be understood that the

same could be the top of a pedestal, or the seat portion of a chair or the like.

In carrying out the invention, there is hingedly connected as at 12 to the top 10 at the under side of the top a plurality of relatively short bars or cleats 13, the bars or cleats 13 being arranged one at each corner of the table and extending substantially at right angles relative to one another.

Each of the bars 13 at that end thereof proximate to an adjacent corner of the table, has suitably secured thereto one end of a supporting leg 14.

Each of three of the legs 14 is connected with a bar 13 to which a second one of said three legs is connected, through the medium of a structure which also serves as a brace, this structure being in the nature of a hinge and consisting of a pair of leafs or links 15, 16 of which, the former or link 15 is fixedly connected as at 17 to the referred bar or cleat 13 by the same screws forming part of one of the hinges 12, or in any other suitable manner (see Figure 4). The latter or link 16 at one end thereof has a sliding hinge connection 18 with one leg 14.

The sliding hinge connection 18 just referred to may be of any suitable structure, however for the sake of example I have shown the same as consisting of a hinge plate 19 secured to an intermediate portion of a leg 14, and a second hinge plate 20 secured to the said end of the link or leaf 16, the last referred to hinge plate 20 being provided with a pair of relatively spaced loop or lugs supporting the hinge pin, and the hinge plate 19 being provided with a single loop or lug slidably engaging the hinge pin between the loops or lugs of the hinge plate 20.

The fourth one of said legs 14 is braced, through the medium of the hinged members 15 and 16 of the referred to combined hinge and brace structure directly from the table top, it being noted from a study of Figure 2 that the member 15 is hinged as at 21 directly to the under face of the table top 10 in alignment with that bar 13 paralleling the edge of the table top, adjacent to which edge the member 15, as at 21 is hinged to the table top.

The members 15 and 16 connecting the said

fourth leg 14 with the table top 10, are provided with means to prevent accidental breaking of the hinge joint between the members 15 and 16. Such means consists in the present instance of a pivoted latch member 22 pivoted to the member 15 and at its free end engageable with a spring keeper member 23 on the leaf 16.

10 The members 15 and 16 of the respective hinges or brace members at their adjacent ends are hingedly connected together as at 24.

15 It will be further noted that the bars 13 are hinged inwardly from the edges of the table top 10, so that when the legs are in a folded condition, that is, in a position engaging the under face of the table top 10 parallel to the bars 13, said legs are disposed between the bars 13 and the corresponding portions of the frame 11. (See Figure 1.)

20 In this manner the legs are locked in a folded position since the legs provide stop means for limiting swinging movement of the bars 13.

25 When the legs are in the folded condition or in the condition shown in Figure 1, and it is desired to swing the legs to a supporting position, two of the legs, namely the referred to fourth leg, and that one of the first named legs with which the bar 13 of the fourth leg is connected by a combined brace and hinge device including the members 15 and 16, are gripped at the points indicated by X in Figure 1. The said fourth leg is first pulled slightly upwardly and outwardly and the 30 said one of the three legs is then pulled upwardly and outwardly, and the movement of this last mentioned leg is transmitted to the remaining two legs, and during continued movement of these legs, the fourth leg is also 35 being pulled to a supporting position so that all of the legs will substantially move into an unfolded or supporting position simultaneously and at approximately the same time one with the other.

40 45 When the legs are in the unfolded or supporting position, latch 22 is engaged with keeper 23 to prevent casual breaking of the hinge connection between the members 15 and 16 and the legs are thus retained braced in supporting position.

To return the legs to the folded or non-supporting position, the latch member 22 is moved out of engagement with keeper 23 and upon movement of the fourth leg to a folded 50 or non-supporting position movement of said leg will be transmitted therefrom to the several remaining legs, the hinge joints between the members 15 and 16 being successively broken as each leg moves to its folded or non- 55 supporting position.

Even though I have herein shown and described the invention as applied to a table, it is apparent that the same may be applied to a chair, pedestal or like article of furniture and accordingly it is to be further under- 60 65

stood that I do not wish to limit myself to the precise form of the invention shown and described herein and accordingly claim all forms of the invention to which I am entitled.

Having thus described my invention, what I claim as new is:

1. In combination, a top member, a plurality of cleats hinged to said top, a leg carried by each cleat, a two-part folding brace for each leg, one part of said brace slidably pivoted to the leg and the other part of said brace fixed to the cleat of the next adjacent leg, whereby the movement of one leg is transmitted through the brace to the next adjacent leg. 70

2. In a table, a table top, a plurality of cleats hinged to said top, a leg carried by each cleat, and a collapsible brace connecting each leg with the cleat of the next adjacent leg. 75

3. In combination, a top member, a plurality of cleats hinged to said top, a leg carried by each cleat, and means connecting each leg with the cleat of an adjacent leg and capable of transmitting movement from any leg to each of the other legs. 80

4. In a folding table, a plurality of cleats hinged to the table, and a leg carried by each cleat so as to fold against the table, an operative connection from each of three legs to the cleat of an adjacent leg, and a similar connection from a fourth leg to the top. 85

5. In combination, a top member, a plurality of supporting legs, means hingedly connecting said legs with said top so as to fold thereagainst, collapsible braces connecting adjacent legs, an additional leg, means hingedly connecting the additional leg to said top, and a collapsible brace having one end slidably pivoted to said additional leg and its opposite end pivoted directly to said top. 90

6. In a folding table, a table top, a plurality of cleats hinged to said top, a leg carried by each cleat, a two-part folding brace for each leg, one part of said brace slidably pivoted to the leg, and the other part of said brace fixed to the cleat of the next adjacent leg, an additional cleat hinged to said top, a leg carried by the last named cleat, and a two-part brace having one part slidably pivoted to the last named leg and the other part pivoted directly to said top. 95

In testimony whereof I affix my signature.

CHARLES G. PASSANANTE.
